UNITED STATES PATENT OFFICE.

GEORGE H. WINTER, OF CHICAGO, ILLINOIS, ASSIGNOR TO W. MOORE THOMPSON, OF CHICAGO, ILLINOIS.

ANTITHUMB-SUCKING DEVICE.

Application filed October 5, 1921. Serial No. 505,670.

To all whom it may concern:

Be it known that I, GEORGE H. WINTER, a citizen of the United States, and a resident of Chicago, county of Cook, and State of Illinois, have invented certain new and useful Improvements in Antithumb-Sucking Devices; and I do hereby declare that the following is a full, clear, and exact description thereof, reference being had to the accompanying drawings, and to the letters of reference marked thereon, which form a part of this specification:

This invention relates to an anti-thumb-sucking device and consists of the matters hereinafter described and more particularly pointed out in the appended claims.

Parents and physicians are familiar with the ugly and harmful habit acquired by small children of sucking the thumb or finger and have realized the failure of the many expedients and means heretofore used to break the habit. The object of the present invention is to provide a device which may be readily attached to the thumb or finger and which will discourage the habit of thumb-sucking,—and this without in any way interfering with the normal use of the thumb or finger.

The advantages of the invention will appear as I proceed with my specification.

In the drawings:—

Fig. 1 is a perspective view on an exaggerated scale of a device embodying my invention;

Fig. 2 is a view representing an end elevation of the same;

Fig. 3 is a view representing a side elevation of the device;—and

Fig. 4 is a view similar to Fig. 2, showing the device adjusted to fit a larger thumb or finger.

Referring now to that embodiment of the invention illustrated in the drawings:—The device consists preferably of two metal rings which are adjustable in diameter and which are spaced apart but are flexibly connected together so that they may be, as a unit, slipped upon and then be adjusted to fit the thumb or finger snugly, with the two rings on opposite sides of the finger joint.

55 5, 6 indicates the rings and 7 the flexible connections, which, as shown, are two connected chain links. Each ring carries a plurality of arcuately spaced, radially directed, blunt-pointed teeth 8 and in the device as

illustrated, the chain-links 7 connecting the rings are attached in eyes formed near the ends of said prongs. Each ring is a narrow, flat band, bent into circular form and having overlapping parts 9, 9 provided with adjacent, radial, apertured flanges 10, 10. 11 indicates a split spring ring which by engagement in two opposed apertures in the two flanges 10 of a ring, locks the overlapping parts of the band to form rings of different diameters, thereby providing for the adjustment of the ring to the size of the thumb or finger. The rings 5, 6 are arranged preferably with the flanges 10 of the rings on the proximate sides of the rings as shown in Figures 1 and 3.

To use the device, it is slipped upon the offending thumb or finger, with the ring 5 just beyond the first joint and the ring 6 on the finger-end side of the joint. The split rings 11 are then removed, the rings 5 and 6 are adjusted to fit the finger or thumb closely,—the fit of the ring 5 being made close enough to prevent it from slipping over the joint—and the split rings are replaced to permanently connect the overlapping parts of the rings. This securely attaches the device to the thumb or finger so that it can not be removed by the child.

When the finger or thumb is now inserted into the mouth, the metal teeth and the chain links connecting them, come in contact with the roof of the mouth and with the tongue, producing discomfort, but not pain, and absolutely prevent the child from bringing the finger itself into contact with these parts, which is necessary in order for it to have the fancied satisfaction due to the sucking of the finger or thumb. The parts of the device, being made of metal, are unyielding and can not be softened by the moisture of the mouth to assume the shape and feel of the thumb or finger, as in the case of preventive devices heretofore used for the purpose.

The rings 5 and 6 with their flexible connections will manifestly interfere in no way with the normal use of the thumb or finger to which the device is applied, but will absolutely discourage, and in a very short time break, the habit. The device is made of parts constructed from a hard, unyielding material and by preference is made of silver or gold at a comparatively small price, or may be made of a cheaper metal, preferably

of a metal which does not tarnish. It is sightly and may be easily kept clean, without removing it, so that there is no objection to its use from a sanitary point of view.

5 The device as thus far described will discourage the child from putting his thumb or finger in his mouth while conscious and awake, that is to say during the time when he will realize that it is impossible to get
10 any satisfaction from inserting the thumb or finger into his mouth with the device upon it. But as he falls asleep or when asleep, the thumb and finger go into the mouth from habit alone and no fancied satisfaction is
15 necessary in order for him to allow the finger or thumb to remain in the mouth. It is therefore preferred to provide the device with an additional or supplemental element which will act to prevent the thumb or finger from entering the mouth after the child
20 has gone to sleep.

To this end I provide a member 12, preferably in the form of a large, light, metal ring, something like a key-ring, which may
25 be attached to the device, as shown in dotted lines in Figure 1 and in full lines in the other figures. Said ring 12 may be readily attached to one of the links of the flexible connections or chains 7 and should be applied as shown, so that when it is attempted
30 to place the thumb, for example, into the mouth, the ring or like element, will be presented against the upper lip, above the mouth, and will thus act as an obstruction
35 to the insertion of the thumb into the mouth.

While in describing a preferred embodiment of the invention, I have referred to several details of mechanical construction, it is to be understood that the invention is
40 in no way limited thereto, except as may be pointed out in the appended claims.

I claim as my invention:

1. A device of the kind described, comprising a plurality of annular split bands having overlapping ends, means for locking the ends of the band together in the desired adjusted position, each band having marginal parts with holes through them, and links extending through said holes and flexibly connecting the bands together.

2. A device of the kind described, comprising a plurality of annular split bands having overlapping ends, means for locking the ends of the band together in the desired adjusted position, each band having radially extending apertured projections, and flexible members extending through the apertures in the projections and connecting said bands together.

60 3. A device of the kind described, comprising two, similar split bands, each band

having a radial flange at its ends with holes therethrough, and radial, apertured prongs spaced from said ends, a split locking ring adapted to be passed through registering holes of the flanges of each band, and links flexibly connecting the radial prongs of one band with the like prongs of the other band.

4. An anti-thumb-sucking device, consisting of a structure made of unyielding material adapted to extend over the major part of the first joint of the thumb to protect said joint from contact with the interior of the mouth, said structure including an adjustable band for attaching it to the thumb back of said joint, and a comparatively large element of unyielding material capable of flexible attachment to said device and adapted to block insertion into the mouth.

5. An anti-thumb-sucking device, consisting of a structure made of unyielding material adapted to extend over the major part of the first joint of the thumb to protect said joint from contact with the interior of the mouth, said structure including an adjustable band for attaching it to the thumb back of said joint, and a comparatively large ring of unyielding material capable of detachable flexible connection to said device and adapted to block insertion into the mouth.

6. In an anti-thumb sucking device, an annular split band adapted to encircle the thumb, radial flanges on each end of the band, said flanges each having holes in them adapted to be brought into registry, means adapted to be inserted through the registering holes to fit the band to the thumb and radial projections on said band adapted to engage the roof of the mouth and the tongue, substantially as described.

7. In a device of the kind described, comprising a plurality of annular split bands having overlapping ends, means for locking the ends of the band together in the desired adjusted position, and flexible non-jointed members connecting said bands together at points spaced from said overlapping ends.

8. A device of the kind described, comprising a plurality of annular split bands having overlapping ends, means for locking the ends of the band together in the desired adjusted position, radial mouth engaging projections on said bands, and flexible means connecting the radial projections on one band with the like projections on the other.

In testimony that I claim the foregoing as my invention, I affix my signature this 1st day of October, A. D. 1921.

GEORGE H. WINTER.
